(57) **CLAIM**

The ornamental design for a cartridge, as shown and described.

DESCRIPTION

FIG. 1 is a perspective view of a cartridge, showing our new design;

FIG. 2 is a front view of the cartridge of FIG. 1;

FIG. 3 is a rear view of the cartridge of FIG. 1;

FIG. 4 is a left view of the cartridge of FIG. 1;

FIG. 5 is a right view of the cartridge of FIG. 1;

FIG. 6 is a top view of the cartridge of FIG. 1; and,

FIG. 7 is a bottom of the cartridge of FIG. 1.

In the drawings, the dashed broken lines depict portions of the Cartridge that form no part of the claim. The dot-dash broken lines represent the boundary of the claimed design and form no part of the claim.

1 Claim, 4 Drawing Sheets
